UNITED STATES PATENT OFFICE

WILFRED A. BEAUCHAMP AND KENNETH J. TOBIN, OF CHICAGO, ILLINOIS, ASSIGNEES
TO CAMEL COMPANY, OF CHICAGO, ILLINOIS, A CORPORATION OF ILLINOIS

DOOR-LOCKING MECHANISM FOR HOUSE CARS

Application filed July 16, 1927. Serial No. 206,154.

This invention relates to door locking mechanism for house cars. In the past, a slidable sealing pin has been used for locking the doors of house cars. 5 This pin was slotted and supported by a rivet extending through the slot. The heads of these rivets frequently crystallize and oxidize in service and snap off during the operation of the locking pin with the result 10 that the pin is thrown away and becomes lost. Further, in producing such pins a molding process is required which produces many imperfect pins due to shrink cracks, hard shots, etc. 15 This invention is designed to overcome the above noted objections in the provision of a pinless locking mechanism which avoids the use of a sealing pin, which can be readily forged and hence more cheaply manufactured 20 and which may be designed to lock the car door in partly open position for ventilating purposes.

The invention comprises the novel structure and combination of parts hereinafter 25 described and more particularly pointed out and defined in the appended claims.

In the accompanying drawings which illustrate certain preferred embodiments of this 30 invention and in which similar reference numerals refer to similar features in the different views:

Figure 1 is a fragmentary elevational view 35 of a pair of house car doors connected by locking mechanism involving this invention.

Figure 2 is a sectional view taken upon the 40 line II—II of Figure 1.

Figure 3 is a view similar to Figure 1 illustrating a modification of this invention.

Figure 4 is a top plan view of the hasp. 45

Figure 5 is a view similar to Figure 1 illustrating a further modified form of the invention.

Figure 6 is a sectional view taken upon the 50 line VI—VI of Figure 5 looking in the direction of the arrows.

Figure 7 is a sectional view taken upon the line VII—VII of Figure 6.

Figure 8 is a front elevational view of one 55 part of the locking mechanism shown in Figure 5.

Figure 9 is a front elevational view of the other part of the locking mechanism that co-operates with the part shown in Figure 8.

Figure 10 is a top plan view of the mechanism shown in Figure 8. 55

Figure 11 is a front elevational view of a part of the mechanism shown in Figure 3.

Figure 12 is a sectional view taken on the line XII—XII of Figure 11.

Referring to Figures 1, 2, and 4 which illustrate the preferred form of this invention, it will be observed that a pair of sliding doors 1 and 2 have been illustrated in connection with this locking mechanism. The locking mechanism consists of a stationary 60 member 3 secured to one door. This stationary member is provided with a stud 4 having an enlarged head 5 which is comparatively narrow. In parallel relation with the stud 4 there is an upstanding lug 6 provided 65 with an aperture 7, as shown in Figure 12, with an aperture 7, as shown in Figure 12, for a purpose that will later appear.

Upon the other door there is secured a hasp fastener 8 which consists of a narrow metal strip having a hook-shaped end 9 which 70 forms a pivot upon which a locking hasp 10 is pivoted to swing in its plane. The hasp 10 is provided with an arcuate slot 11 having opposed notches 12. The hasp 10 is also provided with an upstanding lug 13 having an 75 aperture 14 (Figure 4).

When the doors are closed, the hasp 10 is swung over the headed stud 4—5 until the notches 12 register with the head 5 of the stud when the hasp may be pushed over the 80 head of such stud until the shank thereof engages in the arcuate slot 11. The hasp is then swung until the lugs 13 and 6 come into contact and a sealing wire may be inserted 85 through the apertures of such lugs for sealing the car doors. With reference to Figure 1, it will be noted that the notches 12 are removed from the head of the stud 4 when the doors are locked and that the head of the stud overhangs the margins of the hasp. 90

In Figure 3, there is shown a slight modification of the structure shown in Figure 1. This modification consists in lengthening the hasp to provide a hasp 10^a having a plurality of slots 11 with notches 12. Adjacent each 100

slot there is a lug 13 for cooperation with the lug 6 on the locking member 3 which is also provided with a headed stud 5, as in Figure 1. The hasp 10^a is likewise pivoted upon a support 8. The feature of elongating the hasp allows the doors to be locked and sealed in partially open positions, as shown in Figure 3, for ventilating purposes. In such position the more remote slot 11 from the pivot 10 of the hasp is engaged with the stud 4—5. If it should be desired to lock and seal the door in closed position the first slot 11 from the pivot of the hasp will, of course, be used to engage the pivot stud 4—5. And as each slot 11 has a lug 13 adjacent its inner end for co-action with the lug 6, the locking mechanism may be sealed in either position.

In Figures 5 to 9 a further modification of the invention is shown. In this modification there is shown a locking member 3^a which is adapted to be secured on one of the doors 1 and 2. In the present instance it is shown attached to the door bearing the reference 2. This locking member is provided with a stud 14 which is headless and a lug 15 having an overhanging flange 16 and a closed wall 17 upon one side, whereby a housing is formed which is open upon the side opposite the wall. The overhanging wall 16 has a depending lip 18 at its end which is adjacent the opening to the housing whereby a recess is formed. The lug 15 is provided with an aperture 19 for a purpose that will later appear.

A hasp 20 is secured to the door 2 and is provided with an arcuate slot 21 which is adapted to engage the stud 14. The hasp 20 is pivoted upon a hook 9 which is terminally formed upon a support 8 secured to the door 2 as in the other forms illustrated. At the front end of the hasp 8 there is a lip or lug 22 which is apertured as indicated at 23.

In locking the doors according to this last modification the hasp 20 is swung over the stud 14 so that said stud will engage in the slot 21. The hasp 20 is then swung to bring the lip or lug 22 within the confines of the lug 15, as shown in Figures 6 and 7. In this position the latch 20 is restrained from upward movement by the lip 16 and from lateral movement by the wall 17 and lip 18. It might be mentioned that the hasp 20 is slightly elevated to bring the aperture 23 into registry with the aperture 19. This elevation of the hasp will bring the lip or lug 22 in alignment with the lip 18.

In the form of the invention shown in Figures 5 to 9 the hasp could not be elongated as in the form shown in Figure 3 for the reason that the sealing lugs 15 would be in the way. In the modifications shown in Figures 1 to 3, however, the sealing lugs are located upon one side so that an extension of the hasp is possible. It should be noted that in all forms of the invention the hook shaped end 9 of the hasp fastener is in the same hori-

zontal plane with the pin 4 or 14. Consequently, when the door is locked, the complete strain will be absorbed by the hook 9 and the pin 4 or 14 with the result that there will be no tendency to rupture the sealing wire and allow the hasp to work off the pin and drop down.

It will be appreciated that this locking mechanism eliminates the old form of sealing and locking pin that has been used in the past and that has proved unsatisfactory. Moreover, it reduces the parts of the locking mechanism. In the present instance but two parts are used and there is practically no liability of either part being lost or thrown away as occurred in the use of the sealing pin.

We are aware that many changes may be made, and numerous details of construction may be varied through a wide range without departing from the principles of this invention, and we therefore do not purpose limiting the patent granted hereon, otherwise than necessitated by the prior art.

We claim as our invention:

1. In a latching mechanism for car doors, a stationary member having a stud and an apertured abutment, a pivoted hasp having an arcuate slot engaging said stud, and an apertured lug for abutting relation with apertured abutment for sealing purposes, the pivotal axis of said hasp being substantially in the same horizontal plane as said stud whereby a straight horizontal pull will be maintained upon said hasp.

2. In a latching mechanism for car doors, a stationary member having a stud and a lug with an overhanging lip, a hasp having a pivotal axis in substantially the same horizontal plane as the stud and having an arcuate slot for engaging said stud, said hasp having a lug engaging under said lip, said lugs being apertured for receiving a sealing wire.

3. In a latching mechanism for car doors, a stationary member having a stud and a lug with an overhanging lip and an end wall, a hasp having a pivotal axis in substantially the same horizontal plane as said stud and having an arcuate slot for engaging said stud and an abutment for engaging under the lip of said lug and abutting the end wall, said lug and abutment having a passage for a sealing wire.

4. In a latching mechanism for car doors, a stationary member having a stud and a lug with a recess adjacent said stud, a hasp having a pivotal axis in substantially the same horizontal plane as the stud, a slot for engaging said stud and a lug for fitting the recess of the first-mentioned lug, said lugs having a passage for a sealing wire.

In testimony whereof, we have hereunto subscribed our names at Chicago, Cook County, Illinois.

WILFRED A. BEAUCHAMP.
KENNETH J. TOBIN.
